BOTTLE CLOSURE

Charles E. Paine, Woonsocket, R. I.

Application June 14, 1946, Serial No. 676,623

7 Claims. (Cl. 215—45)

1

This invention relates to bottle closures and has more particular reference to bottle closures adapted to be used for sealing bottles after the original closure member or cap has been removed.

One object of the invention is to provide an airtight bottle closure which may be easily and quickly applied to or removed from the bottle without the use of an instrument.

Another object of the invention is to provide a bottle closure including a cap having a resilient liner and a contractile loop of resilient structure interposed between the cap and the liner and means for contracting the loop.

Another object of the invention is to provide an airtight bottle closure as characterized above, wherein a camming lever operating in a plane tangential to the cap is provided for contracting the resilient loop.

Another object of the invention is to provide an airtight bottle closure as characterized above, wherein means are provided for holding the camming lever in "open" and "closed" positions.

Another object of the invention is to provide an airtight bottle closure as characterized above, wherein the resilient liner is so constructed that upon contraction of the resilient loop an airtight seal is provided around the entire outer periphery of the bottle lip, as well as simultaneously effecting an airtight seal upon the entire top surface of the bottle.

Another object of the invention is to provide an airtight bottle closure as characterized above, wherein the resilient liner serves the dual purpose, upon contraction of the resilient loop, of providing an airtight seal and also of furnishing a resilient reaction to the operation of the camming lever and the contractile loop.

A further object of the invention is to provide an airtight bottle closure which may be economically manufactured and is safe and efficient in operation.

With the foregoing and other objects in view, the invention consists in the construction, combination and arrangement of parts hereinafter described and illustrated in the drawing, in which:

Fig. 1 shows the bottle closure of the invention in front elevation applied to the top of a bottle;

Fig. 2 is a plan view, with a part broken away, of the bottle closure shown in Fig. 1;

Fig. 3 is a central vertical sectional view through the closure member in place upon a bottle top, showing the locking lever in "open" position; and

2

Fig. 4 is a view similar to Fig. 3, but showing the locking lever in "closed" position.

The particular embodiment of the invention shown comprises an outer cap 10; an inner flexible, resilient cap or liner 11; a resilient split ring 12 located between the outer and inner caps and having outwardly turned ends 13, the tips of which are provided with hooks 14; and a locking lever 15 adapted to engage the outwardly turned ends 13 of the split ring 12.

The outer cap 10 is preferably stamped from a single piece of sheet metal or plastic material and comprises a circular top portion 16 and a depending skirt portion 17. The skirt portion is formed with a circumferential inwardly projecting ledge or shoulder 18. At the front of the cap 10, a portion of the top and skirt is pressed outwardly to form a pear-shaped platform or pad 19 which serves as a mounting platform for the locking lever 15.

The inner flexible, resilient liner or cap 11 is preferably made of rubber or other similar material and comprises a circular top portion 20 and a depending skirt portion 21. The skirt portion is formed with a circumferential inwardly projecting ledge or shoulder 22. The shoulder 22 formed on the rubber liner 11 is spaced downwardly from the shoulder 18 formed on the metal cap 10, as clearly shown in Fig. 3. The rubber cap or liner 11 is held within the metal cap 10, preferably by crimping the lower peripheral edge of the skirt 17 of the outer cap 10 over the lower peripheral edge of the skirt 21 of the rubber cap 11, as indicated at 23 in Fig. 3. The resilient, split ring 12 is preferably made of wire and is located between the outer cap 10 and the inner liner 11 and rests upon the shoulder 22 formed on the inner liner 11, with its outwardly turned ends 13 projecting through an elongated slot 24 formed in the pad 19.

The locking lever 15 is mounted on the pad 19 and comprises an elliptical shaped portion 25 having an integral arm 26 projecting upwardly therefrom. The locking lever 15 is provided with an outwardly turned peripheral flange 27 which projects beyond and forms a housing for the hooked ends of the split ring. The member 25 is provided with an elongated slot 28 having rounded ends. The upper and lower edges and the rounded side edges of the slot 28 are provided intermediate their ends with opposing recesses 29, 30, 31 and 32, forming detents for a purpose hereinafter to be described. The outwardly turned ends 13 of the split ring 12 project through the slot 28 formed in the pad 19.

Each of the hooked ends of the split ring 12 are provided with deformations in the form of a projection or shoulder 33. The shoulders 33 bear against the outer surface of the member 25, as clearly shown in Fig. 2, and hold the lever tightly against the pad. In Figs. 1, 2 and 3, the bottle closure is shown in place upon a bottle 34. The bottle 34 represents a conventional beverage bottle and has the usual groove 35 formed therein below the lip 36 forming the mouth of the bottle.

The operation of the device is as follows:

The device is placed on top of a bottle after the original cap or closure member has been removed. When the locking lever is in its "open" or unlocked position, with the arm of the lever vertical, as shown in Figs. 1 and 3, the device may easily be placed on or removed from a bottle top. In this unlocked position, the arm of the lever is held in the vertical position by the detents 30 and 32, which receive the ends of the split ring. The shoulders 33 on the ends of the split ring hold the lever tightly against the pad.

To lock the device on the bottle top, the arm of the lever is revolved in a plane tangential to the cap approximately 90° in either direction, until the ends of the split ring snap into detents 29 and 31. The camming action of the upper and lower edges of slot 28 on the ends of the split ring causes them to approach each other, thereby uniformly decreasing the circumferential length of the split ring 12 and causing the flexible liner 11 to close in about the circumference on the under side of the lip of the bottle, as indicated at 37 in Fig. 4. This results in stretching the rubber liner across the mouth of the bottle, due to the construction of the liner and the fact that the bottom peripheral edge of the liner is securely fastened to the bottom peripheral edge of the outer cap. A seal has now been effected at the top of the bottle, as indicated at 38, and on the outer under side of the lip, as indicated at 37. This seal is maintained and followed up by the internal compression resilience of the rubber liner, by the resilience due to the flexure of the rubber cap in the area under the split ring 12, indicated at 37, by the elasticity of the liner, and by the spring resilience of the ring 12. Thus, the entire outer circumferential area of the bottle lip is sealed. This particular construction greatly widens the range of effective locking and sealing of bottles with widely varying tolerances of neck details.

The opening 24 in the pad 19 formed on the outer cap 10 and the opening 28 in the lever 15 are made of such length as to permit the split ring 12 to expand to a degree to prevent compression of the liner by the ring when the lever is in "open" or vertical position, yet to permit the ends of the ring projecting through the opening 28 to press outwardly against the sides of the opening, due to their resiliency, thereby holding the lever 15 in the "open" or vertical position.

Having thus described the invention, what is claimed is:

1. A bottle closure comprising a cap having a top and a depending skirt having an opening therein, a resilient liner mounted within said cap and having its lower peripheral edge fastened to the lower peripheral edge of said skirt, a split ring provided with hooked ends mounted within said cap and interposed between said skirt and said liner with its hooked ends projecting through said opening; and a lever having an elongated opening therein receiving and engaging said hooked ends and adapted, when operated in a plane tangential to the skirt of the cap, to force the hooked ends toward each other by the camming action of the edges of the elongated opening on said ends, thereby contracting said ring.

2. A bottle closure, as set forth in claim 1, wherein said skirt and said liner are each provided with an inwardly extending circumferential shoulder and wherein said split ring rests on the shoulder formed on said liner.

3. A bottle closure, as set forth in claim 1, wherein the portion of said skirt surrounding the opening formed therein is pressed outward to form a platform having a flat surface upon which said lever is mounted.

4. A bottle closure, as set forth in claim 1, wherein said elongated opening in said lever is provided with an opposing pair of recesses formed in its upper and lower edges intermediate of the ends thereof, and an opposing pair of recesses formed in its end edges intermediate of the ends thereof, said recesses acting as detents to receive the ends of said split ring and cooperating therewith to hold said lever in a vertical "open" position and in a horizontal "closed" position.

5. A bottle closure, as set forth in claim 1, wherein the hooked ends of the split ring are each provided with a shoulder adapted to bear against the outer surface of the lever to hold the lever tightly against the cap and wherein the lever is provided with an outwardly turned peripheral flange extending beyond the hooked ends of the split ring.

6. A bottle closure, as set forth in claim 1, wherein the resilient liner interposed between the split ring and the bottle, is constructed and arranged with sufficient compressibility and space for flexing as to afford resilient reaction to the locking combination of the lever and split ring.

7. A bottle closure comprising a cap having a top and a depending skirt portion having an opening therein, a resilient liner mounted within said cap and having its lower peripheral edge fastened to said skirt, a split ring provided with outwardly turned ends mounted within said cap and interposed between said skirt and said liner with its outwardly turned ends projecting through said opening; and cam means operatively engaged with the outwardly turned ends of the ring for contracting the latter around said liner.

CHARLES E. PAINE.
